UNITED STATES PATENT OFFICE.

CHARLES O. FOEDISCH AND ROY J. FOEDISCH, OF CHICAGO, ILLINOIS.

DOOR-STOP.

1,394,889.

Specification of Letters Patent. Patented Oct. 25, 1921.

Application filed August 16, 1920. Serial No. 403,807.

To all whom it may concern:

Be it known that we, CHARLES O. FOEDISCH and ROY J. FOEDISCH, both citizens of the United States, and residents of Chicago, in 5 the county of Cook and State of Illinois, have invented certain new and useful Improvements in Door-Stops, of which the following is a full, clear, and exact description.

The invention relates to door stops. It 10 is now common practice to rigidly secure door stops to base boards. When thus secured, it interferes with the use of a vacuum cleaner or the ready access to the floor or carpet below the door stop.

15 The object of the present invention is to provide an improved stop which acts as a rigid element in stopping the door but which may be swung out of the way when access to the floor or carpet below the stop 20 is desired.

The drawing is a section of a door stop embodying the invention.

The hollow base 3 is secured to the base-board 4 adjacent the door by screws 5 and 25 the outer surface of this base is convex, as at 6, to form a seat for the body 7, of the stop. Body 7 is provided with a concave seat 8 adapted to engage the convex face 6 of the base. An elastic bumper or tip 9 30 is secured in the outer end of the body 7. A coil-spring 10, disposed in a socket 11 in the body 7, has one of its ends connected to a pin 12 in the base 3 and its other end to a pin 13 in the body 7. This spring serves 35 as a yielding connection which permits the door stop to be swung upwardly, as shown by dotted lines in Fig. 1, when access to the space below the door stop is desired.

Normally, the spring holds the door stop in 40 position shown in full lines so that it will be operative to prevent the door from

striking the base-board, as well understood in the art. When the stop is in normal position, it will be operative to arrest the door. The stop may be easily swung against the 45 force of spring 10 to give access to the space under the stop when sweeping, and when released the spring will automatically retract the stop to its operative position.

The invention is not to be understood as 50 restricted to the details set forth, since these may be modified within the scope of the appended claims, without departing from the spirit and scope of the invention.

Having thus described the invention, what 55 we claim as new and desire to secure by Letters Patent, is:

1. In a door stop, the combination with a base adapted to be attached to woodwork, a stop member having a rigid body and an 60 elastic member secured therein, a spring disposed in said body and connected thereto and to the base, the base and body being provided with bearing surfaces which permit the body to be swung relatively to the 65 base while preventing longitudinal movement of the stop member when it is struck by a door.

2. In a door stop, the combination with a base, adapted to be attached to woodwork, 70 a stop member having a rigid body and an elastic member secured therein, a spring disposed in said body and connected thereto and to the base, the base and body being provided with concavo-convex bearing sur- 75 faces which permit the body to be swung relatively to the base while preventing longitudinal movement of the stop member when it is struck by a door.

CHARLES O. FOEDISCH.
ROY J. FOEDISCH.
